UNITED STATES PATENT OFFICE.

LEONARD G. KIRK, OF NEW YORK, N. Y.

AUTOMATIC AIR-VALVE FOR STEAM-RADIATORS.

SPECIFICATION forming part of Letters Patent No. 605,315, dated June 7, 1898.

Application filed January 15, 1898. Serial No. 666,782. (No model.)

To all whom it may concern:

Be it known that I, LEONARD G. KIRK, a citizen of the United States, residing at New York, (borough of Manhattan,) in the State of New York, have invented certain new and useful Improvements in Automatic Air-Valves for Steam-Radiators, of which the following is a specification.

This invention relates to an air-valve for steam-radiators; and the object of the invention is to improve the action of the valve in such a manner as that it will automatically close the air-outlet as soon as the air has escaped, so that water will not squirt out, as heretofore, in devices of this class.

The invention consists of a base-piece, a casing mounted on the base-piece and provided with an air-outlet at its upper end, and a float arranged in the casing above a deflector near the top of the base-piece to obstruct the direct striking of air and steam which pass through the inlet-passage of the said base-piece against said float, said float being provided with a needle-valve for closing the air-outlet of the casing automatically, when the water from the radiator passes in through the base-piece and acts on said float, as will be hereinafter described and then particularly claimed.

In the accompanying drawings, Figure 1 is a side elevation of a steam-radiator with my improved air-valve attached. Fig. 2 is an enlarged vertical central section, partly in elevation, of the air-valve. Fig. 3 is a transverse section on line 3 3 of Fig. 2, and Fig. 4 is a cross-section on line 4 4 of Fig. 2.

Similar letters of reference indicate corresponding parts.

Referring to the drawings, A indicates the radiator, of any approved form, to which my improved automatic air-valve is attached, as usual.

My device comprises a base-piece or shoe B, which is provided with a screw-threaded pipe extension B', which is screwed into a suitable screw-threaded opening in the radiator A. The base-piece B is provided with an inlet-passage b, which communicates with an enlarged chamber b', formed below a deflector C, which is arranged at the upper part of said base-piece below an internally-screw-threaded flange b² thereon.

At the upper part of the inlet-passage b an auxiliary deflector C' extends above the chamber b', over which chamber is arranged a 55 communicating port or opening d, which establishes communication by means of intermediate passage d', communicating with the chamber b', with the interior of the sheet-metal or other suitable casing E, which at its 60 lower end is screwed into the screw-threaded flange b². Adjacent to the port d and extending downwardly toward the auxiliary deflector C' is a lip C², while a short lip C³ also extends upwardly from the said deflector C. 65

At the upper end of the casing E is a neck E', as usual, into which is screwed an internally-screw-threaded plug F, which is provided with a duct f. Onto the extension E' is fitted, as usual, a cap F', which is provided 70 with suitable orifices.

Arranged within the casing E is a cylindrical float G, which carries on its flat top an upwardly-projecting needle-valve g, while arranged within the lower open end of said 75 float is a diametrical cross-piece g', which at its mid-length is adapted to rest upon an upwardly-projecting and centrally-arranged pin or abutment g², extending from the deflector or diaphragm C. The shape of the float permits an equilibrium of pressure on both sides of the flat top. The point of rest of the float G is so determined as that the needle-valve g has but a slight distance to move in order to move against the valve-seat f' and close 85 the duct f. The float G is guided in its rising and falling movements by means of curved baffles h h', which extend inwardly from about the mid-length of the inner wall of the casing E, the inner edges of said baffles 90 conforming substantially to the curvature of the cylindrical float G. One of the baffles—namely, h'—is arranged directly above the curved port d, so that the air or steam cannot pass directly upwardly and out through 95 the air-outlet, but the air is caused to assume a circuitous or serpentine route.

The operation of my improved air-valve is as follows: When the valves of the radiator are opened so as to permit the steam to enter, 100 the air in the radiator has to be forced out through the duct f. The air will then pass through the inlet-passage b of the base-piece B into the chamber b', out through the port

d, upwardly between the float *G* and the casing *E*, and through the duct *f* to the outer air, the cap *F'* being of course raised. While the air is passing out, it is prevented, by 5 means of the deflector *C*, the auxiliary deflector *C'*, and lips *C²* and *C³*, from acting on the float *G*, so as to raise the same and thereby prevent the escape of the air through the air-duct *f*. When the trapped water rises 10 in the casing *E*, it will rise correspondingly in the float *G*, the bottom of this float being open and admitting the water, as stated, until a sufficient height is reached, when the water will float the float *G*, so as to cause the 15 needle-valve *g* to pass into and against the valve-seat *f'*, thereby closing the valve and preventing the escape of water from the same. When the water recedes and falls back into the radiator *A*, Fig. 1, as usual, the float *G* 20 will then be released and drop down into place, and in so doing leave the air-passage *f* free and open, and the float *G* will continue to rise and fall, as described, until all the air is out of the radiator, whereupon the steam 25 will enter the radiator, as usual, pass thence to and in casing *E*, heat the float *G*, and cause the same to expand and move upward against valve-seat *f'*, thus closing the valve and preventing the escape of steam from same, which 30 condition will remain so long as steam is in contact with the float *G*, keeping same expanded and the outlet of the valve closed.

The float may be composed of hard rubber or vulcanite; but I do not limit myself to this 35 material, as some other materials may be found suitable for the purpose.

Having thus described my invention, I claim as new and desire to secure by Letters Patent—

40 1. In an automatic air-valve for steam-radiators, the combination with a base-piece provided with suitable passages, a deflector at the upper part of the base-piece, an open-

ing at one side of the deflector, an auxiliary deflector in said passages arranged below 45 said opening, and a casing mounted on the base-piece above the deflector and provided at its upper end with an air-duct, of a float arranged within the casing above the said deflector, to one side of said opening and provided with a needle-valve at its upper end 50 adapted to close said air-duct, substantially as set forth.

2. In an automatic air-valve for steam-radiators, the combination with a base-piece, 55 provided with suitable passages, a deflector arranged in a horizontal plane at the upper part of the base-piece, said deflector having an opening at one side and provided adjacent to said opening with an upwardly-projecting 60 lip, and a casing supported on said base-piece above said deflector and provided at its upper end with an air-duct, of a float arranged within the casing above said deflector and to one side of said lip and being provided with 65 a needle-valve adapted to close said air-duct, substantially as set forth.

3. In an automatic air-valve for steam-radiators, the combination with a base-piece, provided with passages through the same, a 70 casing arranged on the base-piece, and provided with an air-duct at its upper end, and baffle-plates projecting inwardly from the inner surface of said casing, of a float arranged in said casing and guided by said baffle-plates 75 in its up-and-down motion, said float being provided with a needle-valve adapted to close said air-duct, substantially as set forth.

In testimony that I claim the foregoing as my invention I have signed my name in presence of two subscribing witnesses.

LEONARD G. KIRK.
